C. E. PATINO

CIRCUIT CONTROLLING DEVICE

Filed July 13, 1925

UNITED STATES PATENT OFFICE.

CARLOS E. PATINO, OF NEW YORK, N. Y.

CIRCUIT-CONTROLLING DEVICE.

Application filed July 13, 1925. Serial No. 43,224.

This invention relates to devices for controlling electric circuits of any kind or class and particularly to control the circuits of a radio receiving apparatus, and the object of 5 the invention is to provide a circuit controlling device with a single operating means whereby multiple circuits may be controlled by such means by movement thereof into several positions to control, for example, the 10 several circuits of a radio receiving apparatus in increasing and decreasing the stages of amplification and for other purposes; a further object being to provide a device of the class specified in the form of a unit adapted 15 to be mounted in connection with the panel of a radio receiving apparatus or in connection with any other support, said unit comprising a plurality of pairs of contact members and a plurality of other contact members 20 movably disposed with reference to the separate pairs of the first named contact members and adapted to complete the circuit between the separate contacts in each pair when in predetermined position; a further object being to provide a device of the class 25 specified in which the second named or multiple contacts are mounted on a single rotatable member, the operation of which is controlled by a knob having an indicator device or pointer 30 thereon or associated therewith; a further object being to construct the pairs of contact members from sheet metal stampings fixedly secured in a body of insulation material, said stampings being so fashioned as to expose on 35 the separate pairs thereof, predetermined contact faces in connection with which the movable contact members operate; and with these and other objects in view, the invention consists in a device of the class and for 40 the purpose specified, which is simple and compact in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

50 Fig. 1 is a diagrammatic view of a radio receiving circuit diagrammatically illustrating my improved circuit controlling device.

Fig. 2 is a longitudinal sectional view through the circuit controlling device.

55 Fig. 3 is a transverse sectional view through the device.

Fig. 4 is a plan view of the device.

Fig. 5 detail views of the several forms of contact plates employed in the construction shown; and,

Fig. 6 is a detail view of a part of the construction shown in Fig. 2, showing a modification.

In Fig. 1 of the drawing, I have diagrammatically illustrated for the purpose of disclosing one use of my invention, the electric circuit of a radio receiving apparatus employing two radio amplification tubes 10 and 11, a detector 12 and two audio amplification tubes 13 and 14. In said figure, 15 represents the antenna connection, 16 the ground connection, 17 the two phone terminals, 18 the plus 120-volt terminal, 19 the two terminals for the loud speaker, 20 the 45-volt plus terminal, 21 the A plus-B minus terminal and 22 the A minus terminal. At 23, I have diagrammatically illustrated my improved circuit control device, with which the circuit wires of the receiving apparatus, which is diagrammatically illustrated, are connected, the device 23 being shown in detail in Figs. 2, 3 and 4 of the drawing.

My improved device comprises a yoke-shaped or U-shaped frame 24 substantially similar to the jack frames commonly employed in apparatus of the class specifically described and rotatably mounted in the frame 24 adjacent the crosshead 24^a thereof is a shaft 25 to the outer end of which is secured an operating knob 26 having a pointer or indicator 27. Secured to the shaft 25 is a stop finger 28 which operates in an elongated aperture 24^b in the crosshead 24^a to limit the rotary movement of the shaft 25. In the structure shown in Figs. 2 and 3 of the drawing a sleeve 29 of insulating material is secured to the shaft 25 within the frame 24 and fixed in and to said sleeve is a plurality of contact fingers 30 mounted in spaced relation and projecting radially from the sleeve 29 and in common alignment longitudinally thereof.

Mounted within the frame 24 above the shaft 25 is a block 31 of insulation material which is of the cross sectional form seen in Fig. 3 of the drawing, and mounted in and secured to said block are a plurality of pairs of contact disks 32, 33, 34, 35, 36, 37 and 38, seven in number, which correspond in number with the number of contact pins 30 employed in the sleeve 29. Said pins 30 are adapted to operate in and between the separate disks of each pair, the pairs of disks 32, 33 and 37

being constructed from the disk A shown in blank form in Fig. 5 of the drawing, while the disks in the contact 36 are constructed from the blank disk B, Fig. 5 of the drawing, 5 the pair of disks 35 being constructed from the blank disk C in said figure, while the pairs of disks 34 and 38 are constructed from the blank D same figure. Each of the blank disks, A, B, C and D have projecting fingers 10 a, b, c and d which project through the top face of the block 31 when said disks are mounted in position and are adapted to be bent over and upon contact plates as hereinafter described. The blank contact plates are also 15 provided with apertures a', b', c' and d' respectively, which serve to anchor said plates in the block 31 and in the construction shown, rods or bolts 39 are passed through these apertures and the block 31 as well as through the 20 frame 24 to secure the block in position and to retain said plates in position. Each of the plates of the separate pairs of contact plates are provided with exposed contact surfaces a'', b'', c'' and d'' respectively which project 25 beyond the inner face of the block 31 as seen in Figs. 2 and 3 of the drawing, whereby the projecting portions of the pins 30 may contact therewith in successively completing the circuits through the several tubes of the radio 30 receiving apparatus as will be apparent.

Secured to the block 31 and projecting above the top face thereof and at the opposite sides thereof are a plurality of terminals 40, 41, 42, 43, 44, 45, 46, 47, 48 and 49 having plates 35, 38 and 36, 37 and 38, in the manner diagrammatically illustrated in Fig. 1 of the drawing, wherein it will be seen that the communication of the separate poles named in the respective order is with one of the plates in each pair. In other words, the terminal 40 is connected with one plate in the pair 32, while the terminal 41 is connected with the 45 other plate in said pair, and further the terminal 40 is connected with one plate of the pair 33 while the terminal 43 is connected with the other plate in said pair, etc.

In Fig. 6 of the drawing, I have shown a 50 slight modification, in which I substitute for the shaft a sleeve construction 25-29 shown in Figs. 2 and 3 of the drawing, a shaft 25^a equivalent to the shaft 25 in operation, and instead of mounting the sleeve of insulating 55 material on the shaft as before described, I provide radio apertures 50 in the shaft 25^a and mount bushings of insulating material 51 therein and in said bushings are mounted contact pins 52 similar, in operation and use, in 60 all respects to the pins 30, the pins being held in place by collars 53 thereon and nuts 54 as clearly seen. It will be understood that any means of insulating the pins 30-52 may be employed, as well as any means for mounting 65 and insulating the separate pairs of contact

plates, and the separate plates in each pair one from the other, the construction shown being only illustrative of one method of carrying my invention into effect.

The operation of my improved device will 70 be readily understood from the foregoing description when taken in connection with the accompanying drawing and the following statement. When the circuit through the radio apparatus is shut off, the shaft 25 is rotated by the knob 26 to bring the contact pins 30 into position diagrammatically shown in Fig. 1 of the drawing. When it is desired to put the apparatus in operation to listen in through phones by contact with the terminals 17, the pins 30 are moved into position to engage the contact faces b'' of the pair of contact disks 36, thus completing the circuit through the battery connections as will be seen, and putting all the tubes 10, 11 and 12 80 into operation. In advancing to the first stage of audio amplification, and in putting the tube 13 into operation, the contact pins 30 are moved into engagement with the contacts on the pairs of disks 32, 35 and 37 and out of 85 contact with the contact members of the pairs of disks 33, thus breaking the connection to the phones and in advancing to the second amplification stage or in putting the tube 14 into operation, the pins 30 are moved into position 90 to engage the contact faces of the pairs of disks 32, 34, 36, 37 and 38, and in this position, the circuit through the contact portions of the pair of disks 35 is broken in addition to the breaking of the phone circuit 95 as previously stated.

From the foregoing, it will be apparent that in a partial revolution of the knob 26 of the circuit controlling device 23, the entire receiving apparatus may be moved from a shut off position into a fully operating position, or position in which all of the tubes of the apparatus are functioning, and it will be understood that any number of stages of amplification may be employed, the controlling device being constructed to suit the particular apparatus in connection with which the same is employed, the showing and description as herein set out being only illustrative of one method of carrying my invention into effect. 105 It will also be apparent that my improved circuit controlling device is not necessarily limited for use in connection with radio receiving apparatus, as the same may be employed in connection with any electric circuit 110 wherein a plurality of electric devices are employed, and it is desirable to control the several circuits from a point of unitary control instead of employing a multiplicity of switches, jacks or similar devices, and various other changes in and modifications of the construction herein shown and described 115 may be made within the scope of the appended claims without departing from the spirit of my invention or sacrificing its advantages. 120

Having fully described my invention, what I claim as new and desire to secure by Letters Patent, is:—

1. A circuit controlling device of the class described comprising two units insulated one from the other, each of said units being provided with a plurality of electric contact members, said members being insulated one from the other in the respective units, the members of one unit being adapted to cooperate with the members of the other unit in the completion of the circuits therethrough and one of said units being movable relatively to the other, the arrangement of the contact portions of the members of one of said units being in irregular relation whereby the members of the other unit may engage one or more of the contacts of the members of the other unit, and the members of one of said units being arranged in pairs and the members in each pair constituting independent contacts.

2. A circuit controlling device of the class described comprising two units insulated one from the other, each of said units being provided with a plurality of electric contact members, said members being insulated one from the other in the respective units, the members of one unit being adapted to cooperate with the members of the other unit in the completion of the circuits therethrough and one of said units being movable relatively to the other, the arrangement of the contact portions of the members of one of said units being in irregular relation whereby the members of the other unit may engage one or more of the contacts of the members of the other unit, the members of one of said units being arranged in pairs and the members in each pair constituting independent contacts, and the circuit wires being connected with each of the contact members in said pairs.

3. A circuit controlling device of the class described comprising two units insulated one from the other, each of said units being provided with a plurality of electric contact members, said members being insulated one from the other in the respective units, the members of one unit being adapted to cooperate with the members of the other unit in the completion of the circuits therethrough and one of said units being movable relatively to the other, the arrangement of the contact portions of the members of one of said units being in irregular relation whereby the members of the other unit may engage one or more of the contacts of the members of the other unit, the members of one of said units being arranged in pairs and the members in each pair constituting independent contacts, the circuit wires being connected with each of the contact members in said pairs, and the other members being adapted to complete the circuit between the contacts in each pair.

4. A device of the class described comprising

ing a frame, a member rotatably mounted in said frame, a plurality of electric conductors on said member in spaced relation and insulated one from the other, and a body of insulation material mounted in said frame adjacent said rotatable member and a plurality of pairs of contact disks mounted in said body, the separate pairs of disks being insulated one from the other, and the disks in each pair from each other, said pairs of disks having contact faces of different dimensions exposed for engagement with the conductors of said rotatable member in the movement of said member, means on said body for placing the disks in each pair in predetermined electric circuits, and said conductors being adapted to complete the circuit between the separate disks in each pair in the several positions thereof, and means for limiting the movement of said rotatable member.

5. A circuit controlling device of the class described comprising a plurality of pairs of electric conducting members, said members having exposed contact faces of different dimensions in the separate pairs, and means for completing the circuit between the electric conducting members in each pair.

6. A circuit controlling device of the class described comprising a plurality of pairs of electric conducting members, said members having exposed contact faces of different dimensions in the separate pairs, and means for completing the circuit between the electric conducting members in each pair, said means comprising a member provided with spaced and insulated conductors movably disposed with reference to the contact faces of the separate pairs of members.

7. A device of the class described comprising a U-shaped frame, a member rotatably mounted in said frame adjacent the crosshead thereof, a plurality of conducting pins mounted in connection with said member and insulated one from the other, a block of insulation material mounted in said frame adjacent said member, a plurality of contact disks mounted in said block, said disks being arranged in pairs, the separate pairs being insulated one from the other and the disks in each pair insulated from each other, means for coupling circuit wires with the separate disks, and said disks being provided with projecting contact faces of different dimensions in the separate pairs, and said pins being adapted to be moved into and out of engagement with the contact faces of the separate pairs of disks to frictionally pass therebetween to complete the circuit between the contact faces in each pair.

8. A device of the class described comprising a U-shaped frame, a member rotatably mounted in said frame adjacent the crosshead thereof, a plurality of conducting pins mounted in connection with said member and insulated one from the other, a block of insulation material mounted in said frame adjacent said

member, a plurality of contact disks mounted in said block, said disks being arranged in pairs, the separate pairs being insulated one from the other and the disks in each pair insulated from each other, means for coupling circuit wires with the separate disks, and said disks being provided with projecting contact faces of different dimensions in the separate pairs, said pins being adapted to be moved into and out of engagement with the contact faces of the separate pairs of disks to frictionally pass therebetween to complete the circuit between the contact faces in each pair, and the contact faces on the separate pairs of disks being arranged in different position with relation to a predetermined number of the other pairs of disks.

9. A device of the class described comprising a U-shaped frame, a member rotatably mounted in said frame adjacent the crosshead thereof, a plurality of conducting pins mounted in connection with said member and insulated one from the other, a block of insulation material mounted in said frame adjacent said

member, a plurality of contact disks mounted in said block, said disks being arranged in pairs, the separate pairs being insulated one from the other and the disks in each pair insulated from each other, means for coupling circuit wires with the separate disks, said disks being provided with projecting contact faces of different dimensions in the separate pairs, and said pins being adapted to be moved into and out of engagement with the contact faces of the separate pairs of disks to frictionally pass therebetween to complete the circuit between the contact faces in each pair, and the contact faces on the separate pairs of disks being arranged in different position with relation to a predetermined number of the other pairs of disks, and means for limiting the rotary movement of said member in two directions.

In testimony that I claim the foregoing as my invention I have signed my name this 10th day of July, 1925.

CARLOS E. PATINO.
